UNITED STATES PATENT OFFICE

EDWIN F. BRITTON, JR., OF MAPLEWOOD, NEW JERSEY, ASSIGNOR TO MONROE CALCULATING MACHINE COMPANY, OF ORANGE, NEW JERSEY, A CORPORATION OF DELAWARE

CALCULATING MACHINE

Application filed March 23, 1929. Serial No. 349,449.

The invention relates to dual selector mechanism for calculating machines, whereby an amount selected by a single setting operation may be registered independently on 5 different numeral wheels.

According to the invention, two relatively reversible series of digit selector members are adjusted for differential action by a common setting-up mechanism, the invention consisting in the novel construction and combination of parts, as set forth in the appended claims.

In the accompanying drawings illustrating the invention;

15 Fig. 1 is a plan view of a calculating machine embodying the invention in one form;

Fig. 2 is a front elevation of the keyboard mechanism, with parts broken away;

20 Fig. 3 is a section taken on line 3—3 of Fig. 1;

Fig. 4 is a section taken on line 4—4 of Fig. 1;

Fig. 5 is a detail front elevation of the reversing mechanism for the lefthand actuator 25 set.

The selector mechanism illustrated in these drawings is a modification of that disclosed in United States patent to E. E. Phinney Number 1,399,652, issued December 6, 1921 30 and entitled "Setting-up means for calculating machine." Numerous features of the motor-driven machine herein illustrated are disclosed in co-pending application Serial No. 337,073, filed February 2, 1929 by E. F. Britten, Jr., and entitled "Registering mechanism."

According to the form of the invention illustrated herein, two series of numeral wheels 13 and 33 are mounted on a shaft 34 extending longitudinally on the carriage 2. Amounts to be registered in the wheels 13 and 33 are set up on keyboards 18 and 35, the keys of which are each depressible to adjust a pair of rock bars 19 as fully disclosed in the Phinney patent hereinbefore referred to. Each 40 pair of rock bars 19 transmit the setting to a pair of selector gears 5, wherefrom the amounts are transferred to the wheels 13 or 33 upon rotation of selector shaft 4 and of 45 the related carry shaft 73 or 36.

The rock bars 19 are provided with lower extensions with which connector plates 37 are adapted to engage, these plates serving to connect each column of keys of the keyboard 18 with rock bars 19 of corresponding columns of the keyboard 35. As will be noted upon inspection of Figure 2, while the connector plates serve to transmit movement from the rock bars 19 of the keyboard 18 to the rock bars of keyboard 35, they are so arranged that setting movement of a key of the keyboard 35 will have no effect upon the rock bars 19 of the keyboard 18. 55

The connector plates 37 are mounted on a frame 38 and means are provided for raising and lowering the frame 38 to active or inactive position, such means including a shift lever 39 and spring slick device 40. The connector plates 37 may remain in engagement with the rock bars 19 of the one keyboard, while the engaging portions of the plates related to the rock bars of the other keyboard may be beveled, so that if any of the related keys are in depressed position when the connector plates are raised into engagement, the plates will be cammed into full engaging position. 60

As illustrated in the co-pending application hereinbefore referred to, and in accordance with the well-known Monroe calculating machine, the selector and carry shafts related to the keyboard 18 may be rotated to transfer the set-up amounts to the numeral wheels 13 by means of a hand crank 3 or an electric motor A, clutch and reverse gear mechanism being provided between the motor and carry shaft 73. Crank handle 3 is rotated in one direction in calculations of addition and multiplication, and in a reverse direction for calculations in subtraction and division, forward and reverse rotation of the machine during motor operation being governed by add and subtract keys 120 and 121, a division lever 318, and multiplier keys 261. 75

The carry shaft 36 related to the keyboard 35 may be connected with the carry shaft 73 related to the keyboard 18, by means of forward and reverse gearing 41, controlled by a three-position shift lever 42. The middle position of shift lever 42 leaves shafts 36 and 80 95 100

73 disconnected, and in this position of the parts, no registration will occur on numeral wheels 33. Movement of lever 42 from neutral position in one direction will couple the 5 shafts 36 and 73 for rotation in unison, while movement of said lever from neutral position in the opposite direction will connect shafts 36 and 73 by means of reversing gearing 41, so that forward or reverse rotation of shaft 10 73 will be transmitted as reverse or forward rotation of shaft 36, whereby an amount set up on one of the keyboards will be registered additively and an amount set up on the other keyboard will be simultaneously registered 15 subtractively, or vice versa.

Suitable multiplier and quotient registers 85 and 88 may be provided as shown in the Britten application, and one of these registers may be provided with tens carry mechanism 20 and reversing gearing, under the control of change lever 399, as therein fully disclosed. The registration wheels 13, 33, 85, and 88, may be set to zero registering position by means of one or more clearing devices 409, and levers 25 418 may control the clearing or non-clearing of any selected series.

The keyboard clearing and repeat-non-repeat mechanism disclosed in the Britten application is applied to the keyboard 18, and is 30 duplicated for the keyboard 35. Owing, however, to the connector plates 37, this hand and automatic clearing means enables certain new methods of operation to be used.

According to this arrangement, clear keys 35 12 and 43 are provided, depression of either of these keys serving to depress the "0" keys of the related keyboard, and thereby to rock locking bails 6 and release any other keys of such keyboard which may be in depressed 40 position. When either non-repeat key is set, rotation of the machine will serve to actuate a universal clear-out bar 23 engaging the locking bails 6 of the related keyboard and acting to release any depressed keys thereof.

If an amount were set up in the three right-hand columns of keyboard 18, for instance, with the connector plates 37 in active position, the same setting would be made on the three right-hand selector columns of the 50 keyboard 35. If, now, another amount were set on the three left-hand columns of keyboard 35, and the machine were operated, the right-hand setting would be registered in numeral wheels 13 and in numeral wheels 33, while the left-hand setting would be registered in the other numeral wheels 33 only. A new amount might now be set in the three left-hand columns of the keyboard 35, or, if the clear key 43 were depressed, the setting 60 in the three left-hand columns may be cleared without interference with the setting in the right-hand columns of either keyboard.

The last described operation is possible because the setting in the right hand columns 65 of keyboard 35 are controlled by the keys of

the keyboard 18, such keys not being released upon operation of the clear key 43. If, in the operation above described, the left-hand non-repeat key had been set, the amount set up in the left-hand columns would have been 70 cleared automatically without disturbing the setting in the right-hand columns.

From the foregoing it will be evident that keyboard 18 is a master keyboard wherefrom settings may be made in the auxiliary selector mechanism related to keyboard 35, such settings being entirely independent of the control means related to the auxiliary keyboard. The selector mechanism of the master keyboard will respond correctly to the additive and subtractive rotations indicated by the different operation control members 120, 121, 261, and 318, while the selector members related to the auxiliary keyboard 35 may not 80 so respond.

I claim:

1. In a calculating machine having two series of numeral wheels and two series of differential selector members related each to a series of wheels; two laterally aligned series of laterally adjustable column setting members related each to a series of selectors, slide bars adjustable to connect the corresponding setting members of each series to act in unison, and means for reversing the operation of one series of selector members relative to the operation of the other series.

2. Settable digit selecting means for calculating machines having a plurality of ordinary setting members and unitary means for releasing the selecting means in a plurality of orders from set position; master means adjustable to active position and adapted to set the selecting means of any selected orders and to maintain such setting upon operation of said releasing means, means for holding said master means as adjusted, and unitary means for releasing the selecting means from such master setting with the master means held in active position.

3. Settable digit selecting means for calculating machines having a plurality of ordinary setting members and unitary means including a manually operable clear key for releasing the selecting means in a plurality of orders from set position; master means adjustable to active position and adapted to set the selecting means of any selected orders and to maintain such setting upon operation of said releasing means, means for holding said master means as adjusted, and unitary means including a manually operable clear key for releasing the selecting means from such master setting with the master means held in active position.

4. Settable digit selecting means for calculating machines having a plurality of ordinary setting members and non-repeat mechanism settable to release the selecting means automatically from set position; means for 130

setting the selecting means of any selected orders and for maintaining such setting upon operation of said non-repeat mechanism.

5. In a calculating machine having two series of numeral wheels, two series of differential selector members related each to a series of wheels, two series of column setting members related each to a series of selectors, means for holding the column setting members of one series in adjusted position, and means for connecting the corresponding setting members of each series to act in unison; means for releasing the setting members from the connecting means, operable to release the 10 setting members of one series from adjusted 15 position.

6. In a calculating machine having two series of numeral wheels, two series of differential selector members related each to a series of wheels, two series of column setting members related each to a series of selectors, means for holding the column setting members of one series in adjusted position, and means for connecting the corresponding setting members of each series to act in unison; means for adjusting the connecting means from inactive to active position, adapted to 20 cooperate with the holding means to adjust the setting members of one series to correspond to the adjusted position of the related 25 members of the other series.

In testimony whereof I affix my signature.
EDWIN F. BRITTON, JR.
